CLAIM

The ornamental design for a telescoping vacuum wand assembly as shown and described.

DESCRIPTION

FIG. 1 is a perspective view of a telescoping vacuum wand assembly showing the new design, in which the telescoping vacuum wand assembly is illustrated in a first configuration. FIG. 2 is a perspective view thereof showing the telescoping vacuum wand assembly in a second, extended configuration. FIG. 3 is an enlarged rear view thereof. FIG. 4 is an enlarged front view thereof. FIG. 5 is a top view thereof. FIG. 6 is a bottom view thereof.

FIG. 7 is a right-side view thereof; and, FIG. 8 is a left-side view thereof.

In these drawings, the solid lines illustrate the claimed ornamental design, whereas broken lines illustrate unclaimed subject matter and form no part of the claimed design. The telescoping vacuum wand assembly is shown with symbolic breaks in its length with pairs of dash-dot broken lines in FIGS. 1, 2, and 5-8 to indicate indeterminate length. The appearance of any portion of the article not shown between the break lines forms no part of the claimed design.
